OTHER PUBLICATIONS

U.S. Appl. No. 29/639,219; Display Screen With Animated Icon: Madhur Khandelwal, filed Mar. 5, 2018.

Primary Examiner — Darlington Ly

Assistant Examiner — Daniel J Domino

(74) Attorney, Agent, or Firm — Finnegan, Henderson, Farabow, Garrett & Dunner LLP

(57) **CLAIM**

The ornamental design for a display screen with icon, as shown and described.

DESCRIPTION

The sole FIGURE is a front view of a display screen with icon, showing the new design.

The broken lines of uneven length show the display screen and form no part of the claimed design.
